ADJUSTABLE TABLE LAMP OR SIMILAR ARTICLE

Samuel J. Koch, Great Neck, N.Y., assignor to SOSS
Manufacturing Company, Detroit, Mich., a corporation of Maine

Filed Dec. 29, 1964, Ser. No. 83,204

Term of patent 14 years

(Cl. D48—20)

FIG.1.

FIG.2.

FIG.5.

FIG.4.

FIG.3.

FIG.6.

FIG. 7.

FIG. 8.

FIG. 9.

FIG. 10.

FIG. 11.

FIG. 12.

FIG. 1 is a perspective view of an adjustable table lamp or similar article showing my new design in its open and extended position.

FIG. 2 is a top view thereof.

FIG. 3 is a side view thereof.

FIG. 4 is a rear view thereof.

FIG. 5 is a front view thereof.

FIG. 6 is a bottom view thereof.

FIG. 7 is a perspective view thereof in its collapsed position.

FIG. 8 is a top plan view thereof as shown in FIG. 7.

FIG. 9 is a side elevation thereof as shown in FIG. 7.

FIG. 10 is a front view thereof as shown in FIG. 7.

FIG. 11 is a rear view thereof as shown in FIG. 7.

FIG. 12 is a bottom view thereof as shown in FIG. 7.

The dominant features of my design reside in the portions shown in full lines.

I claim:

The ornamental design for an adjustable table lamp or similar article, substantially as shown and described.
